(57) **CLAIM**

The ornamental design for a flying camera drone, as shown and described.

DESCRIPTION

Flying camera drone

Fig. 1.1 is a front perspective view of the flying camera drone showing our new design;

Fig. 1.2 is a top plan view thereof;

Fig. 1.3 is a bottom plan view thereof;

Fig. 1.4 is a front view thereof;

Fig. 1.5 is a rear view thereof;

Fig. 1.6 is a left side view thereof; and

Fig. 1.7 is a right side view thereof.

The broken lines shown in the figures represent portions of the flying camera drone that form no part of the claimed design.
